(57) **CLAIM**

The ornamental design for an ear piece guide set, as shown and described.

DESCRIPTION

FIG. 1 is a rear perspective view of the left ear piece guide shown in a position of use;

FIG. 2 is a rear perspective view of the right ear piece guide shown in a position of use;

FIG. 3 is a rear perspective view of the right ear piece guide as shown in FIG. 2, the left ear piece guide of FIG. 1 is a mirror image thereof;

FIG. 4 is a top plan view of the right ear piece guide shown in FIG. 3;

FIG. 5 is a rear elevational view of the right ear piece guide shown in FIG. 3;

FIG. 6 is a right side elevational view of the right ear piece guide shown in FIG. 3;

FIG. 7 is a front elevational view of the right ear piece guide shown in FIG. 3;

FIG. 8 is a bottom plan view of the right ear piece guide shown in FIG. 3; and,

FIG. 9 is a left side elevational view of the right ear piece guide shown in FIG. 3.

The broken line showing of the person and small profile headgear assembly in FIGS. 1 and 2 illustrates the environment of the claimed design and forms no part thereof.

1 Claim, 2 Drawing Sheets
